UNITED STATES PATENT OFFICE.

JOSEPH H. SMITH AND DANIEL C. RIPLEY, OF BIRMINGHAM, AND ALOIS KWOCZALLA, OF LAWRENCEVILLE, PENNSYLVANIA.

DESIGN FOR A JELLY-GLASS AND CAP.

Specification forming part of Design No. 5,055, dated June 27, 1871.

To all whom it may concern:

Be it known that we, JOSEPH H. SMITH and DANIEL C. RIPLEY, of Birmingham Borough, and ALOIS KWOCZALLA, of Lawrenceville, in the county of Allegheny and State of Pennsylvania, have invented a new and useful Design for Jelly-Glass and Cap; and we do hereby declare the following to be a full, clear, and exact description thereof, reference being had to the accompanying drawing making a part of this specification, in which—

Figure 1 is a side elevation of a jelly-glass and cap illustrative of our improved design, and Fig. 2 is a lower face perspective view of the cap.

Like letters of reference indicate like parts in each.

Our improved design consists in the combination of a beaded jelly-cup with a cap, both flanged, and provided with a hook or hooks, and a spring-catch by which to attach it to the cup.

To enable others skilled in the art to use our improved design, we will proceed to describe the same.

The glass cup *b*, made in the usual way, has

a bead, *a*, around its mouth. The cap *d*, of sheet metal, has a downward flange, *c*, of sufficient depth to protect the contents of the cup *b* from dust, &c., and on one side of the edge it has a hook, *e*, which catches under the bead *a*. Opposite to it, or nearly so, is a spring-catch, *e'*, which curves inward to engage the bead *a*, and then outward so as to furnish an easy means of removal. The hooks and catches may be duplicated, if so preferred, without departing from the scope of the design.

What we claim as our invention, and desire to secure by Letters Patent, is—

The design for jelly-glass and cap, of the form hereinbefore described and shown.

In testimony whereof we, the said JOSEPH H. SMITH, ALOIS KWOCZALLA, and DANIEL C. RIPLEY, have hereunto set our hands.

JOSEPH H. SMITH.
ALOIS KWOCZALLA.
DANIEL C. RIPLEY.
